DROPHEAD TYPEWRITER DESK

James R. Clark and Frederick W. Ackerman,
Rochester, N. Y., assignors to Yawman and
Erbe Mfg. Co., Rochester, N. Y., a corporation
of New York

Application February 29, 1932, Serial No. 595,744

14 Claims. (Cl. 312—24)

Our invention relates to drophead typewriter desks and is particularly concerned with the provision of improved hardware or mechanism for swinging the typewriter supporting shelf from its operable to its idle or storage position in conjunction with the opening and closing of the usual cover portion of the desk top.

A general object of our invention is to provide a four point suspension for the typewriter shelf when in its operable position, to make the mounting for the typewriter more solid and free of vibration. It has been found that if the typewriter shelf is left free to vibrate, the typewriter frame will be set in motion together with the shelf by the impacts of the carriage. As a result the carriage is not always evenly progressed step by step under the influence of the carriage return strap and winding drum. The carriage might be released to move a space at a time which coincides with the vibration of the typewriter moving in the opposite direction with the result that the momentum given the carriage counteracts the spring tension on the carriage, and the following key hits the paper before the carriage has been fully moved to its next stop. It has also been found that the keys which are mounted at the outer ends of relatively flexible rods, are liable to be set in vibration by the vibrating of the frame, with the result that they do not center accurately when they hit the paper or with the result they are so thrown out of their normal paths that they bind with other type heads moving into or out of position.

It has been previously proposed to pivot the front shelf near its front edge—either by a fixed pivot or by a sliding pivot or its equivalent in the form of guiding rollers—and pivotally to connect the shelf near its rearward edge with an extension of the link which controls the rearward edge of the cover. In such case the link and its extension constitute a beam which serves to swing the shelf between its upper and lower positions by, and in accordance with, the movement of the cover. In some instances, instead of providing the sliding movement at the forward pivot of the shelf, the necessary sliding has been permitted by a slotted pivot of the beam to the rearward edge of the shelf.

We have discovered that an inherent objection to operating the shelf by this beam which guides the rearward edge of the cover is that the swing movement imparted to the cover is first fast, then slow, and then fast (assuming that the cover is moved at a uniform speed). This tends to "slam" the shelf to its upper and lower positions.

On the other hand in those types of drophead actuating mechanisms wherein the shelf is supported cantilever-wise from the front pivot, the operating connection between the cover and the shelf is such as to impart the more desirable class of movement to the shelf—a movement which is first slow, then fast, and then slow. This tends to ease the shelf, and the typewriter which it carries, into its upper and lower positions. The operating connection between the cantilever supported shelf and the cover is of varied types but most often comprises a toggle between the cantilever support of the shelf and the forward portion of the cover. The objection to the cantilever support however is that it is not as solid as a four point suspension.

An object of our invention is to overcome these respective defects of these two types of mechanisms, while at the same time retaining their respective advantages. In general we accomplished this by retaining the usual cantilever type of suspension with the toggle between it and the forward edge of the cover, to operate the shelf, that is, to swing it from its upper to its lower position. We also employ the extension on the link, which guides the rearward edge of the cover, to provide a rearward support for the shelf and thereby effect a four point suspension. But we do not employ the beam to operate the shelf. We bring it into position only to support the shelf.

Another object of our invention is to provide a truly effective four point suspension which compensates for inaccuracies in the mechanism due to manufacturing or assembly variations or to variations due to wear of the parts.

The foregoing, together with other objections, features, and advantages of our invention are set forth in the following description of a preferred specific embodiment thereof which is illustrated in the accompanying drawings wherein:

Fig. 1 is a perspective view of a typewriter desk showing the cover down and the shelf up;

Fig. 2 is a transverse vertical section through the desk at its mid point;

Fig. 3 is a section similar to Fig. 2 but showing the shelf down and the cover up;

Fig. 4 is a perspective view of the operating mechanism alone, when the cover has been moved but a few inches upwardly from its down position of Fig. 2;

Fig. 5 is a front elevation of a fragment of the desk shown in the position of Fig. 1;

Fig. 6 is a vertical section taken on the line 6—6 of Fig. 3;

Fig. 7 is a plan section taken on the line 7—7 of Fig. 2;

Fig. 8 is a vertical section taken on the line 8—8 of Figs. 5 and 7 showing the cushioning pad between the frame and the shelf;

Fig. 9 is a vertical section taken on the line 9—9 of Fig. 2 through a lateral edge of the shelf showing how the end of the beam supports the rearward portion of the shelf; and

Fig. 10 is a view similar to Fig. 9 but showing a modified construction.

The desk here shown comprises similar left and right pedestals 15 and 16 having inner walls 15a and 16a. The spaced pedestals are connected at their backs by a back panel 17, across the rearward part of their bottoms by the bottom panel 18 and on the tops by the connecting portion 19a of the top 19. Forwardly of the connecting rear portion 19a, the top is cut away between the pedestals to receive the cover 20. At their front edges the pedestals are connected by a cross rail 21 of a wide U-shape. The legs of the U are secured to the adjacent corner legs of the pedestals, while the horizontal web of the U-shaped rail extends just below the depending front rail 22 of the cover 20, when the cover is in its closed position.

The cover is mounted to swing between a horizontal upper position (Fig. 3) and a vertical lower position (Fig. 2). The mounting is effected by a pair of links on each lateral side. One link 23 of the pair is pivoted at 24 to the under side of the top adjacent its forward edge, the other end of the link being pivoted at 25 to a bracket 25' secured to the inner panel 15a of the pedestal 15. The other link 26 of the pair is pivoted to the underside of the top 20 at 27 near its rear edge. The other end of the link 26 is pivoted at 28 to the inner panel of the pedestal.

At each lateral side, the shelf 30 carries a cantilever bracket 31 which is pivoted at 32 to the inner panel of the pedestal and which carries an upwardly extending arm 33. Each arm 33 is pivotally connected by a link 34 with an extension 35 of the link 23, thereby forming a toggle.

When the cover is in the open position of Fig. 2, the toggle is approximately in its dead center position.

As the forward edge of the top 20 is pulled upwardly and forwardly to its closed position, the link 23 swings through approximately 180°, first breaking the toggle and then finally again bringing the pivots of the toggle into approximate alignment, but with the toggle pivot proper at the other side of the stationary pivot 25. This swinging of the link 23 results in a general reciprocal motion of the link 34 which swings the cantilever support 31 downwardly. Assuming a uniform arcuate speed of movement for the link 23, the pull imparted to the link 34, and consequently the down swinging of the shelf 30, is first slow, then fast, and again slow. This avoids jerking of the typewriter and eases the typewriter and shelf into its lowermost position. The rear edge of the shelf 30 contacts the rail 18' at the forward edge of the bottom wall 18, when the shelf is swung down to its lowermost position. By the mechanism described, the shelf comes gently to rest upon the rail 18' instead of violently impacting it.

Similarly, when the cover is moved from its closed position of Fig. 3 to its open position of Fig. 2, the typewriter and shelf are not initially

jerked upwardly, and when they come to their uppermost position, they approach it gently.

Each link 26, which guides the rearward portion of the cover in its movement between its upper and lower positions, carries a bell crank extension 36. When in the position of Fig. 2, the extension 36 is substantially vertical. At its free end the extension 36 carries a roller 37 which, when in the position of Fig. 2, engages a short channel shaped guide member 38 secured to the lateral edge of the shelf 30 near its rearward edge. Inasmuch as the shelf is actuated by the toggles 34 and 35, there being no connection between the bell crank extension 36 and the shelf, the roller 37 very rapidly swings out of engagement with the shelf-carried channel 38 when the cover 20 is swung upwardly from its position in Fig. 2. As shown in Fig. 2, this is so because the first few inches of upward movement of the cover 20, acting through the toggles, give but very little down swinging movement to the shelf while a considerable movement is given to the bell crank extension.

Thus while the toggles serve at all times to position the shelf, the bell crank extensions 36 of the levers 26 function only when the shelf is substantially at its upper position. When the desk is in the position of Fig. 3, the extensions 36 lie idle, having swung out of contact with the channels 38. When the cover is lowered from its position of Fig. 3 toward the position of Fig. 2, the extensions 36 swing upwardly to contact their respective shelf-carried channels 38 after the toggles, actuated by the links 23, have swung the shelf substantially to a horizontal position. The final arcuate movement of the bell crank extensions 36 is to cam the rearward edge of the shelf upwardly to its final horizontal position.

Theoretically, the right and left pivots 32 and the right and left bell crank extensions 36 provide a four point suspension for the shelf. In practice, manufacturing inaccuracies, inaccuracies of assembly, and wear of the parts would probably preclude an absolute four point suspension. Further, the rearward portion of the shelf might rest upon the bell crank extensions 36, rather than being firmly held against them. This might permit vibration also.

To remedy these objections, we introduce a resilient element at some point in the supporting mechanism. Preferably it consists in a pair of rubber pads 39 clamped by bolts 40 to the underside of the shelf 30 near its forward edge in such position that the pads are interposed between the bottom of the shelf and the top flange 130 of the front cross rail 21. The head of the bolt 40 may conveniently be set to clear the top flange as shown in Fig. 8.

As the shelf is swung upwardly to its horizontal position, the forward edge of the shelf 135 swings downwardly toward the cross rail 21, because the pivots 32 are located rearwardly of the front edge of the shelf. As the shelf comes to its final horizontal position, the pads 39 are clamped between the shelf and rail. The final swinging of the bell crank extensions 36 acts with effective leverage to cam the rearward edge of the shelf upwardly and thereby compress the resilient pads 39. Inasmuch as the upper toggles have come substantially to a dead center relation, at the end of the movement, substantially the entire weight of the cover 20 is utilized to swing the bell crank 26, 36, to effect this final compression of the pads 39. One advantage gained is that the pads 39 act as resilient stops 150

to check a violent impact of the cover 20 against the bottom wall 18.

The more important advantage however is that the resiliency of the pads compensates for any practical inaccuracies and permits a substantial four point suspension of the typewriter shelf. It also holds the rearward edge of the shelf tightly against the extensions 36, and otherwise prevents rattling or vibration.

10 The desk here shown is of sheet steel construction, although I contemplate that the mechanism may also be applied to the usual wood desk constructions. If the desk be of sheet steel construction, an upstanding wall 41 extending 15 along the lateral and back sides of the shelf may conveniently be provided. As here shown the shelf top 30 carries depending side flanges 42 and the wall 41 carries bottom flanges 43 which extend inwardly beneath the flanges 42. 20 The flanges 42 may be spot-welded to the walls 41 whereby the walls also serve to reinforce the shelf. At the sides of the shelf, the wall 41 conceals the operating toggles which occupy the narrow space between the inner panels of the pedestals and the margins of the shelf. At the back of the shelf, the wall 41 serves to close up the opening between the shelf and the depending front rail 22 of the cover when in the position of Fig. 2. 25 The cantilever brackets 31 may be secured to the lateral edges of the shelf by bolting them as at 44 to the bottom flanges 43 of the wall 41. The shelf is further stiffened by cross channels 45 and 46 which preferably are located at 30 or near the points where the front and back feet respectively, of the typewriter are to be clamped. As shown in Fig. 9, the cross channels preferably do not extend to the edges of the shelf, but only to the bottom flanges 43 of the wall 41. This 35 permits the use of a bottom plate 47 for the shelf with upturned lateral flanges 48, without the necessity of weakening the reinforcing effect of the flanges 48 by slotting them for the passage of the cross channels.

40 In Fig. 10 we have illustrated a modification wherein outwardly extending lateral channel 38 is dispensed with, and instead the roller 37 of the extension 36 bears directly against the underside of the shelf. A channel may be provided by beads 49 in the bottom flange 43 of the wall 41 to serve the purpose of the channel 38 in positioning the roller 37 against undue lateral movement. In Fig. 10 we have shown the cross channel 46 as extending to the lateral edge 45 of the shelf, and with the flange 48 of the bottom plate 47 notched to receive the cross channel.

45 While we have illustrated and described these specific embodiments of our invention, we contemplate that many changes may be made therefrom without departing from the scope or spirit of our invention.

We claim:

1. A drophead typewriter desk comprising a desk body, a cover, a typewriter shelf, means for supporting and guiding the cover from a forward horizontal closed position rearwardly and downwardly to a vertical open position, for pivotally mounting the shelf near its forward edge to swing about a horizontal pivot, and, by interconnection with the cover, for swinging the shelf about its pivotal mounting from an upper horizontal position to a lower oblique position in conjunction with the closing of the cover, and other means actuated by the cover but not contributing substantially to the swinging of the shelf for sup-

porting the rearward portion of the shelf when the shelf is in its upper horizontal position.

2. A drophead typewriter desk comprising a desk body, a cover, a typewriter shelf, means for supporting and guiding the cover from a forward horizontal closed position rearwardly and downwardly to a vertical open position, for pivotally mounting the shelf near its forward edge to swing about a horizontal pivot, and, by interconnection with the cover, for swinging the shelf about its pivotal mounting from an upper horizontal position to a lower oblique position in conjunction with the closing of the cover, and other means actuated by the cover but not operatively connected with the shelf when the shelf is in its downswung position for supporting the rearward portion of the shelf when the shelf is in its upper horizontal position.

3. A drophead typewriter desk comprising a desk body, a cover, a pair of links pivotally mounted on the desk body, one pivotally connected to the cover near its forward edge and the other pivotally connected to the cover near its rearward edge, for guiding and supporting the cover from a closed horizontal position downwardly and rearwardly to a vertical open position, a typewriter shelf, means for pivotally mounting the typewriter shelf on the body near the forward edge of the shelf, means including said first mentioned link for swinging the shelf between an upper horizontal position and a lower oblique position and means normally operatively independent of the shelf for supportingly engaging the rearward portion of the shelf when the shelf is in its upper horizontal position.

4. A drophead typewriter desk comprising a desk body, a cover, a pair of links pivotally mounted on the desk body, one pivotally connected to the cover near its forward edge and the other pivotally connected to the cover near its rearward edge, for guiding and supporting the cover from a closed horizontal position downwardly and rearwardly to a vertical open position, a typewriter shelf, means for pivotally mounting the typewriter shelf on the body near the forward edge of the shelf, means including said first mentioned link for swinging the shelf between an upper horizontal position and a lower oblique position, and an extension on the second mentioned link normally operatively independent of the shelf but adapted to supportingly engage the rearward portion of the shelf when the shelf is in its upper horizontal position.

5. A drophead typewriter desk comprising a desk body, a cover, a pair of links pivotally mounted on the desk body, one pivotally connected to the cover near its forward edge and the other pivotally connected to the cover near its rearward edge, for guiding and supporting the cover from a closed horizontal position downwardly and rearwardly to a vertical open position, a typewriter shelf, means for pivotally mounting the typewriter shelf on the body near the forward edge of the shelf, means including said first mentioned link for swinging the shelf between an upper horizontal position and a lower oblique position, and an extension of said second mentioned link constituting therewith a bell crank, said extension being operatively independent of the shelf when the shelf is in its downward position but swinging into a substantially vertical position below the shelf when the shelf is swung to its horizontal position for supporting the rearward portion of the shelf.

6. A drophead typewriter desk comprising a

- desk body, a cover, a pair of links pivotally mounted on the desk body, one pivotally connected to the cover near its forward edge and the other pivotally connected to the cover near its 5 rearward edge, for guiding and supporting the cover from a closed horizontal position downwardly and rearwardly to a vertical open position, a typewriter shelf, means for pivotally mounting the typewriter shelf on the body near 10 the forward edge of the shelf, and means including said first mentioned link for swinging the shelf between an upper horizontal position and a lower oblique position, said second mentioned link extending on the opposite side from 15 its pivotal mounting on the desk and constituting with the link a beam, said extension supportingly engaging the rearward portion of the shelf to support the shelf when in its horizontal position.
- 20 7. A drophead typewriter desk comprising a desk body, a cover, means for supporting and guiding the cover from an upper horizontal closed position downwardly and rearwardly to a vertical open position, a typewriter shelf pivotally mounted at its forward edge, mechanism actuated by movement of the cover for swinging the shelf between an upper horizontal position and a lower oblique position, said mechanism swinging the shelf with a movement which is, in reference to 25 the movement of the cover, first slow, then fast, and then slow, said cover guiding and supporting mechanism including a link pivotally mounted on the body and pivotally connected to the rearward portion of the cover, an extension of said link 30 constituting therewith a bell crank, which extension is swung with a movement which is first relatively slow, then faster, said extension engaging the shelf to support its rear portion when the shelf is swung to its upper position.
- 35 8. A drophead typewriter desk comprising a desk body, a cover, a pair of links for supporting and guiding the cover from an upper horizontal closed position downwardly and rearwardly to a vertical open position, each link being pivotally mounted at one end on the body, the other ends of the links being pivotally connected respectively to forward and rear portions of the cover, a typewriter shelf, means for mounting the shelf on the body to swing about its forward portion 40 from a horizontal upper position to an oblique lower position, an extension on the forward link constituting a toggle lever, a toggle link connecting the extension with the forward portion 45 of the shelf for swinging the shelf by the movement of the cover, an extension of the rearward link constituting therewith a bell crank, said extension being normally operatively independent of the swinging of the shelf but engaging the shelf when the shelf is in its upper position, for 50 supporting its rearward portion.
- 55 9. The combination with a desk, of a typewriter shelf pivotally mounted near its forward portion on the desk to swing upwardly from a lower position to an upper horizontal position, a cushioning member spaced from said pivotal mounting for resiliently limiting the upward swinging of the shelf to its final upper position, and shelf operating mechanism removed from 60 said pivotal mounting and said cushioning member for swinging the shelf to its final position against the cushioning member and for lockingly clamping the shelf against the cushioning member with the latter under resilient compres-
- sion whereby the cushion member reacts upon the mechanism, urging the shelf in the opposite direction of swing.
10. A drophead typewriter desk comprising a desk body, a cover mounted to move from a closed horizontal position rearwardly and downwardly to an open vertical position, a typewriter shelf mounted to swing about its forward portion from an upper horizontal position to a lower oblique position, mechanism interconnecting the shelf and cover to swing the shelf by movement of the cover, resilient means tending to limit the final upward swinging of the shelf, and other means connected with the cover and actuated by its movement for swinging the shelf into its final upper position against said resilient means. 80
11. A drophead typewriter desk comprising a desk body, a cover mounted for movement from a horizontal closed position downwardly and rearwardly to an open vertical position, a typewriter shelf, means for pivotally mounting the shelf at its forward portion but rearwardly of its forward edge, mechanism interconnecting the shelf and cover for swinging the shelf between an upper horizontal position and a lower oblique position by the movement of the cover, a cross rail mounted on the desk body and extending beneath the shelf forwardly of its pivotal mounting, a resilient member interposed between the shelf and the cross rail, and other mechanism connected with the cover and actuated by the movement thereof for operatively engaging the shelf to force the shelf into its final upward position against the force of said resilient member. 85
12. A typewriter desk comprising a desk body, a rectangular shelf, a cover, and means affording a four point suspension of the shelf from the desk body comprising, at each lateral side of the shelf, a pivotal mounting for the shelf near its forward portion, cover actuated mechanism engaging the shelf near its rearward portion for forcing the rearward portion of the shelf to its final horizontal position, and a resilient member forward of the pivotal mounting for the shelf, interposed between the shelf and the body and compressed by said forcing action on the cover for compensating for any practical inaccuracies in a theoretical four point suspension 100 and for holding the shelf against vibration said mechanism locking the shelf against the resilient member when thus compressed. 105
13. A typewriter desk comprising a desk body, a typewriter shelf, means for pivotally mounting the shelf adjacent its forward portion to swing from an upper horizontal position to a lower oblique position, a cover, means interconnecting the cover and the shelf to swing the shelf between its two positions, channel brackets at the lateral sides of the shelf at its rearward portion, and pivotally mounted levers also connected with and operated by movement of the cover having rollers at their free ends, adapted to engage said channels to support the rearward portion of the shelf when the shelf is in its upper horizontal position. 115
14. A drophead typewriter desk according to claim 13, wherein the channels are mounted beyond the lateral edges of the shelf. 120
